UNITED STATES PATENT OFFICE.

ERNEST M. OLSON, OF CHICAGO, ILLINOIS.

CONTROL MECHANISM FOR LAMPS.

Application filed October 20, 1921. Serial No. 508,959. 100

To all whom it may concern:

Be it known that I, ERNEST M. OLSON, a citizen of the United States, residing at Chicago, in the county of Cook and State 5 of Illinois, have invented a new and useful Improvement in Control Mechanism for Lamps, of which the following is a specification.

This invention relates to improvements in 10 control mechanism for lamps, and is especially adapted for use in connection with lamps, such as head-lights, mounted on automobiles, boats, aeroplanes, and other moving things. For the purpose of explaining 15 the features of my invention, I have here shown it as applied to a head-light mounted at the front end of an automobile. The features and advantages of the invention will appear from the following specification.

20 In that form of device embodying the features of my invention, shown in the accompanying drawings, Figure 1 is a view in side elevation of the front end of an automobile having mounted thereon a lamp controlled by my improved mechanism; Fig. 2 is a view in front elevation thereof; Fig. 3 is a vertical sectional view taken as indicated by the line 3 of Fig. 1; and Fig. 4 is a vertical sectional view taken as indicated by the line 4 of Fig. 2.

As shown in the drawings, 10 indicates a radiator at the front end of an automobile. Mounted on the radiator, in any suitable manner, such as by the bracket 11, is a housing 12 which is substantially in the shape of an inverted frustrated cone, somewhat flattened at the backside where it lies adjacent the front surface of the radiator. The upper end of the casing 12 carries a circular turn-table 13 having diametrically-arranged upwardly projecting posts 14 which carry pivotally supported between their upper ends the lamp or head-light 16. Rotation of the turn-table is limited to substantially 360° by means of the pin 19 adapted to engage with the stop 21.

Projecting upwardly through the center of the turn-table 13 is a sleeve 23 carrying the pinion 24 at its upper end. Rotation 50 of the turn-table 13 with respect to the sleeve 23 is permitted. The lower end of the sleeve 23 projects into a stationary bridge member 25 which is held in position within the casing 12 by means of the screws 27 at its end. 55 Mounted on the sleeve 23 by means of the set-screw 28 is a bevel-gear 29 lying between the

turn-table 13 and the bridge member 25. Arranged between the bevel-gear 29 and the bridge member 25 is a cork washer 30 for a purpose to be hereafter explained.

The lamp 16 carries on its under sides a segment 32 provided with teeth 33 engaging with the teeth on the pinion 24, so that rotation of the sleeve 23 and pinion 24 will move the lamp 16 where it is pivoted between the supports 14, to make it point upwardly, downwardly or horizontally, as desired.

The bridge member 25 has a downwardly projecting part 37 provided with a hole 38 in which is rotatably mounted one end of a tube 39 which extends through a suitable bearing 40 in the backside of the casing 12 and thence backwardly through the radiator to a position within reach of the driver of the automobile. The inner end of the tube 39 is provided with a suitable operating wheel 41 by which the same may be rotated. The tube 39 carries at its forward end a double gear wheel 42 comprising the bevel-gear 43 and pinion 44. The double gear wheel 42 is mounted on the sleeve 39 by means of the set-screw 45 and lies between the back wall of the casing 12 and the part 37 of the bridge member 25. The double gear wheel 42 is sufficiently thin to permit a certain amount of longitudinal movement of the sleeve 39. It is normally held in the rearmost position by means of the spiral spring 45a. It is shown in this position in Figure 4 of the drawings. When in this position the teeth of the pinion 44 mesh with the teeth 50 of the circular gear 51 mounted on the under surface of the turn-table 13. By means of this construction, rotation of the sleeve 39 will cause rotation of the turn-table 13 and consequent turning of the lamp 16 in a horizontal plane. Such turning of the lamp in a horizontal plane will also operate to tilt the same for the following reasons:

The bevel-gear 29 is mounted on the sleeve 23 sufficiently low so that there will be some pressure of this bevel gear on the cork washer 30, thus yieldingly holding the sleeve 23 against rotation. Because of this construction, when the turn-table 13 rotates, the sleeve 23 will remain stationary. This will cause the segment 32 to roll around on the stationary pinion 24, thus tilting the lamp. The parts are so arranged that when the tube 39 is rotated by means of the hand wheel or knob 41 to turn the lamp 16 to the right, this turning will cause the lamp to

be inclined downwardly. The value of this construction is obvious at a glance. When the vehicle is going straight ahead, the lamp is set to point substantially horizontal. 5 When approaching another vehicle, the car turns to the right. When this is done, the wheel 41 is operated to turn the lamp to the right and this turning also serves to tilt the lamp so that it will point slightly downwardly, thus removing the glare from the driver of the approaching vehicle and also serving to better illuminate the ground to the right and close to the front of the vehicle. After the vehicles have passed, when 10 the straight road is again taken, and the lamp turned to the front again, it is automatically elevated to the requisite height for straight driving.

Tilting of the lamp 16 may also be accomplished, as desired, without turning the same in a horizontal plane. This is done by pushing the tube 39 forward until the teeth of the bevel gear 43 engage with the teeth of the bevel-gear 29. This forward movement of the tube 39 serves to disengage the teeth of the gear 44 from the teeth 50 of the gear 51. When the bevel gears 43 and 25 29 are engaged, rotation of the operating wheel 41 will serve to rotate the sleeve 23 and pinion 24 to raise or elevate the lamp 16, as desired. The spring 45^a serves to slide the tube 39 backward when the pressure is released, in order to again engage the teeth of the gear 44 with the teeth 50 of the circular gear 51.

Means are provided for turning the lamp off or on as follows: Mounted within the tube 39 and adapted to slide therein is a rod 60 carrying at its inner end a knob 61. The rod 60 carries at its outer end a knife switch 63 through which the circuit leading to the lamp 16 is led. Pulling or inward movement of the rod 60 serves to close the switch and outward movement to open the same.

The casing 12 is supported at the bottom by a vertically arranged tapered member 70 suitably mounted in any manner at the forward end of the automobile. The wires 75

leading to the lamp 16 are led downwardly through this casing.

Although I have shown and described certain embodiments of my invention, it is to be understood that it is capable of many modifications. Changes, therefore, in the construction and arrangement may be made without departing from the spirit and scope of the invention as disclosed in the appended claims in which it is my intention to claim all novelty inherent in my invention as broadly as possible in view of the prior art.

I claim:

1. In a control mechanism for lamps, means for simultaneously rotating a lamp in a horizontal plane and inclining the same downwardly, said means comprising a circular turn-table carrying the lamp, means for rotating the turn-table, a stationary pinion, and a segmental toothed rack mounted on the lamp, engaging with the stationary pinion.

2. In a control mechanism for lamps, a turn-table carrying a lamp, pivotally supported thereon, a segmental toothed rack mounted on the lamp and engaging with a pinion, means for rotating the turn-table, and means for rotating the pinion engaging with the segmental toothed rack on the lamp.

3. In a control mechanism for lamps, a turn-table carrying a lamp, pivotally mounted thereon, a segmental toothed rack on the lamp engaging with a pinion, and adjustable operating means adapted to be moved to a position to rotate the turn-table, or to a position to rotate the pinion engaging with the segmental toothed rack on the lamp.

4. In a control mechanism for lamps, a turn-table carrying a lamp, pivotally mounted thereon, a segmental toothed rack, mounted on the lamp and engaging with a pinion, yielding means for holding said pinion stationary, means for rotating the turn-table, and means for rotating the pinion.

ERNEST M. OLSON.
